UNITED STATES PATENT OFFICE.

ROY A. McCARTY, OF WILKINSBURG, PENNSYLVANIA, ASSIGNOR TO WESTINGHOUSE ELECTRIC & MANUFACTURING COMPANY, A CORPORATION OF PENNSYLVANIA.

COLLECTOR RING.

1,404,871.

Specification of Letters Patent. Patented Jan. 31, 1922.

Application filed May 17, 1920. Serial No. 381,800.

To all whom it may concern:

Be it known that I, ROY A. McCARTY, a citizen of the United States, and a resident of Wilkinsburg, in the county of Allegheny and State of Pennsylvania, have invented a new and useful Improvement in Collector Rings, of which the following is a specification.

My invention relates to a dynamo-electric machine and it has particular relation to collector-rings adapted to be mounted on the rotor of such a machine.

The object of my invention is to provide a means for resiliently mounting a set of collector-rings that shall be of simple design, relatively inexpensive to manufacture and of great durability and which may be so constructed that all of the collector-rings shall be equally resilient.

Heretofore, it has been customary, in machines embodying a plurality of collector-rings, to mount the central rings on a centrally disposed annular support, by means of radially-extending supporting arms. The collector-rings on both sides of the centrally disposed collector-rings were mounted by means of supporting arms which projected angularly from the planes of the collector-rings to the centrally disposed support on which the central collector-rings were mounted. The central collector-ring, being positioned more rigidly than the others by reason of the radial support, did not yield uniformly with them, so that the pressure of the brushes on the rings was unequal. This method of mounting collector-rings is fully set forth in Letters Patent, No. 702,599, granted to R. Seigfried on June 17, 1902.

By my invention, I provide a set of collector-rings of substantially the same flexibility, so that all of the brushes in engagement therewith are subjected to substantially equal pressure, thereby improving the contact made between the brushes and the rings, lessening the chattering of the brushes and causing them to wear uniformly.

Briefly speaking, my invention consists of providing resilient supporting arms for the central collector-ring which will make it as flexible, with respect to the co-operating brushes, as are the other collector-rings of the set.

For a better understanding of my invention, reference may now be had to the accompanying drawings, of which Fig. 1 is

a view, in side elevation, of a plurality of collector rings mounted on an annular support by means of supporting arms embodying my invention. Fig. 2 is a view, in end elevation, of the parts shown in Fig. 1. Fig. 3 is a detail cross-sectional view, taken along the line III—III of Fig. 2, of one of the outer rings. Fig. 4 is a detail cross-sectional view, taken along the line IV—IV of Fig. 2 of one of the supporting arms of the centrally disposed collector-ring. Fig. 5 is a detail side elevational view of that portion of the central collector-ring and its supporting arm shown in Fig. 4.

Referring more particularly to Figs. 1 and 2, a plurality of collector-rings 1, 2 and 3 are mounted, by means of supporting arms 4, 5 and 6, respectively, upon the centrally disposed supporting member 7. The annular support 7 is securely mounted upon a rotatable shaft 8 on which is also mounted a dynamo-electric machine motor 9. Conductors 10, as best shown in Fig. 2, extend from the collector-rings 1, 2 and 3 to the windings of the rotor 9. The supporting arms 4 and 6 of the collector-rings 1 and 3, respectively, project angularly to the centrally disposed supporting member 7 and are provided, at their inner ends, with bosses 11 and 12, respectively. The centrally disposed ring 2 is provided with supporting arms 5 which curve tangentially inward from the collector-ring 2. The inner end of the arm 5 is provided with a boss 13, similar to the bosses 11 and 12. The bosses 11, 12 and 13 are all secured, at their inner ends, to the supporting member 7 by means of bolts 14.

Fig. 3, which is a sectional view along the line III—III of Fig. 2, shows a portion of the outer ring 1 provided with a laterally extending supporting arm 4 having a lug 11, at the inner end thereof, through which the stud-bolt 14 projects to secure it to the supporting member 7, as previously described. The lug 11 is provided with a beveled portion 15, which fits into an annular groove 16 in the supporting member 7 and is insulated therefrom by means of rings 17, composed of insulating material. The bolts 14 are provided with tubular coverings (not shown) and insulating washers 18 to insulate them from the bosses 11. The supporting arms 6 of the collector-ring 3 are similarly mounted and differ only from supporting arms 4 in that they project in the opposite

direction from the plane of the collector-ring which they support.

Figs. 4 and 5 show a portion of the central collector-ring 2 provided with a tangentially extending supporting arm 5 having a lug 13 at its inner end, as previously described. By making the arm 5 of the proper cross-section and length it may be made to have the same degree of resiliency as the arms 4 and 10 6. It is apparent that the supporting arms 5 are substantially in the same plane as is collector-ring 2. The bosses 13, at the inner ends of the supporting arm 5, are mounted in a manner similar to that described for 15 the bosses 11 and 12 or the supporting arms 4 and 6.

It will be observed by those skilled in the art that collector-rings mounted in accordance with my invention will be uniformly 20 resiliently mounted and thus cause their cooperating brushes to wear uniformly and, therefore, for a longer period of time and will improve the contact made between the brushes and the collector-rings; also that 25 apparatus constructed in accordance therewith will be relatively simple and inexpensive to manufacture, strong and durable in operation and relatively easy to assemble and repair.

30 While I have shown a preferred form of my invention, it may be subjected to slight modifications which do not depart from the spirit thereof. Therefore, I desire to be limited only by the scope of the appended 35 claims.

I claim as my invention:—

1. In a dynamo-electric machine, the combination with a rotatable member, of a collector-ring mounted thereon and provided 40 with a spider member having resilient supporting arms disposed in substantially the same plane as said collector-ring.

2. In a dynamo-electric machine, the combination with a rotatable member, of a collector-ring mounted thereon and provided 45 with bent supporting arms disposed in substantially the same plane as said collector-ring.

3. In a dynamo-electric machine, the combination with a rotatable member, of a collector-ring mounted thereon and provided 50 with tangentially extending supporting arms

disposed in substantially the same plane as said collector-ring.

4. In a dynamo-electric machine, the combination with a rotatable member, of a collector-ring provided with flexible supporting arms disposed in substantially the same plane as said collector-rings, means for securing said arms to said support, and means 55 for insulating said collector-rings from said support.

5. The combination with an annular support having a grooved end surface, of a collector-ring provided with flexible supporting arms disposed in substantially the same plane as said collector-ring, the inner ends of said supporting arms being adapted to engage the grooved end surface of said annular support, insulating washers disposed 65 intermediate said support and said supporting arms, and bolts securing the inner ends of said supporting arms to said annular support. 70

6. The combination with a rotatable support, of a plurality of collector-rings arranged in side-by-side relation and each provided with supporting arms that project substantially into the same plane, all of said rings having substantially the same degree 80 of resiliency, and means for fastening said arms to said support. 75

7. The combination with a rotatable support, of three collector-rings arranged in side-by-side relation provided with supporting arms that project approximately into the plane of the central collector-ring, said supporting arms having substantially the same degree of resiliency and means for fastening said arms to said support. 85 90

8. The combination with an annular support, of a plurality of collector-rings each provided with supporting arms, the inner ends of all said arms projecting into substantially the same plane and being so constructed as to support each of said rings with substantially the same degree of resiliency and means for securing the inner ends of said arms to said annular support. 95

In testimony whereof, I have hereunto 100 subscribed by name this 30th day of April, 1920.

ROY A. McCARTY.
